CLAMPING COMB

Siegfried Behr, Flushing, N. Y., assignor to Ben Hur Products, Inc., New York, N. Y., a corporation of New York

Application August 18, 1934, Serial No. 740,404

2 Claims. (Cl. 132—22)

This invention relates to a combined hair comb and clamp.

A primary object is to provide a device of this kind that can be securely attached to the hair and is prevented from becoming displaced in the hair.

Another object is to provide such a device that is ornamental and attractive in appearance.

Still another object is to provide a device of 10 this kind that is simple in construction and economical to manufacture.

The invention will be better understood from the description thereof to follow taken in connection with the accompanying drawing in 15 which—

Figure 1 is a front elevation of my improved device.

Figure 2 is a side view thereof.

Figure 3 is a sectional view taken on the plane 20 of line 3—3 of Fig. 1.

Figure 4 is a sectional view taken on the plane of the line 4—4 of Fig. 1.

Figure 5 is a view showing the improved device in position on the head of a wearer.

Referring to the drawing, my improved device includes a comb indicated generally at 10 having an upper solid portion 11 and spaced depending teeth 12. The teeth are shown wavy in form but may be shaped as desired. This 30 comb may be made of pyroxilin compound or any other suitable material, and is slightly curved as shown in Fig. 2.

Pivotedly mounted on the upper solid portion 11 of the comb, near the top thereof and on each side of the center thereof is a clamping member 13. Each clamping member is formed with a hub portion 14 which is loosely mounted on a pivot pin 15 which passes through an opening in the solid portion of the comb and is fastened to the other side of the solid portion by a turned over portion 16. These clamping members are shown as shaped like wings and are so positioned on the pivot pin and relative to the teeth of the comb that a portion thereof slides over and overlaps said teeth. It will be understood that these clamping members may take any desired shape or form so long as a portion thereof is adapted to slide over the teeth. These clamping members are preferably made of the 45 same material as the comb.

In using my improved comb and clamp, the comb is inserted into the hair so that the hair will protrude out through the teeth, the clamp-

ing members having first been turned so that no portions thereof cover the teeth of the comb to a position such as the left hand clamping member of Fig. 1. One or both of the clamping members are then turned by a protruding portion on its pivot so that a portion thereof will slide over the hair and teeth and clampingly hold said hair between said teeth and portion.

In addition to firmly attaching the comb to the hair, the clamping members provide ornaments for the hair.

It will be understood that the form of my improved device shown in the drawing is for illustration only and that variations in details may be made without departing from the principle 15 of the invention and I desire to be limited only by the state of the prior art and the appended claims.

I claim:

1. In a device of the kind described, a comb comprising a curved body portion and teeth thereon, a clamping member having a solid body, a pivot pin mounting said member rotatably on the convex side of said comb, said clamping member comprising a hub portion and a pair 25 of lever arms thereon, one of said arms covering a part of the teeth on said comb and a part of the hair protruding therefrom pressing it against the convex comb surface, the other arm extending beyond the outline of said comb 30 forming a handle for operation of said clamping member outside of the hair surface.

2. In a device of the kind described, a comb comprising a curved body portion and teeth thereon, a pair of clamping members each having a solid body, a pair of pivot pins symmetrically spaced from the median line of said comb in the body portion thereof, each pin holding one of said members rotatably connected to the convex side of said comb, each of said members having a hub portion surrounding said pin and a pair of arms extending therefrom, one of said arms covering a part of the teeth on said comb and a part of the hair protruding therefrom pressing it against the convex comb surface, the other arm extending beyond the outline of said comb 40 forming a handle for operation of said first arm outside of the hair and when in clamping position forming in cooperation with the second clamping member a symmetrical figure uncov- 45 ered by the hair.

SIEGFRIED BEHR.
